[57] CLAIM

The ornamental design for a storage container for software discs, as shown in described.

DESCRIPTION

FIG. 1 is a perspective view of a storage container for software discs shown in partial open position;

FIG. 2 is a right side elevational view of FIG. 1 with the lid shown in full open position;

FIG. 3 is a top plan view of FIG. 2;

FIG. 4 is a front elevational view of the storage container in closed position;

FIG. 5 is a top plan view of FIG. 4;

FIG. 6 is a right side elevational view of FIG. 4, the left side being a mirror image;

FIG. 7 is a bottom plan view of FIG. 4; and,

FIG. 8 is a rear elevational view of FIG. 4.
